UNITED STATES PATENT OFFICE.

CYRUS S. DEAN, OF FORT ERIE, CANADA, ASSIGNOR OF ONE-HALF TO THE SHERWOOD MANUFACTURING COMPANY, OF BUFFALO, NEW YORK, A CORPORATION OF NEW YORK.

TURNER FOR FLUE-CLEANERS.

No. 821,613.

Specification of Letters Patent.

Patented May 29, 1906.

Application filed March 1, 1904. Serial No. 195,958.

To all whom it may concern:

Be it known that I, CYRUS S. DEAN, a subject of the King of England, residing at Fort Erie, in the county of Welland, Province of Ontario, and Dominion of Canada, have invented a new and useful Improvement in Turners for Flue-Cleaners, of which the following is a specification.

My invention relates to turners for flue-cleaners, and more particularly to turners for flue-cleaners of the type known as the "hammer" type.

The object of my invention is to produce a slow but continuous automatic movement in rotation when the hammer is in action for the purpose of distributing the blows of the hammer equally over the interior surface of the flue.

In the drawings herewith, Figure 1 is a longitudinal section taken through the axes of the working parts, showing my device applied to a hammer. Fig. 2 is a top plan view. Fig. 3 is a cross-section on the line xx of Fig. 1. Figs. 4, 5, 6, and 7 are views of a modified form of my invention, in which Fig. 4 is a top plan view. Fig. 5 is a longitudinal section at right angles thereto. Fig. 6 is a view looking from the right in Fig. 4. Fig. 7 is a section on the line yy of Fig. 4. Fig. 8 is a detail view of my ratchet mechanism on a larger scale.

I will first describe the construction shown in Figs. 1 to 3, inclusive. Since the hammer is no part of my invention, the same need not be described further than to state that the driving-plate 1 is actuated by the movement of the piston 2. Pivotaly mounted within the body 3 of the turner is a worm 4. Rigidly mounted upon a non-rotating part 5 is a gear 6. When the gear 6 is held rigid and the worm 4 is rotated, it is evident that the worm 4 will cause the body 3 and the body of the hammer directly connected therewith to rotate. I produce this rotation of the worm 4 in the following manner: Pivoted upon a pin 7, secured to the body 3, is a lever 8, which at its outer end has a pin 9, which projects upwardly and travels in a slot 10 in the driving-plate 1. This slot 10 is inclined slightly to the line of travel of the driving-plate 1, so that the pin 9 is caused to move laterally and to reciprocate over a small arc of a circle the head 11 of the lever 8. The

worm 4 is provided with a serrated or ratchet-toothed head 12, and pivoted at 13 and 14 upon the lever 8 are dogs 15 and 16, which engage upon the serrated surface of the head 12.

The action is as follows: When the plate 1 has given reciprocatory movement by the action of the steam upon the piston, the inclined slot 10 will cause transverse movement of the pin 9, and consequently cause movement over a small arc of a circle of the head 11. This movement will cause the two dogs 15 and 16 to come alternately in contact with the head 12 and alternately travel up upon the serrated surface of said head—that is to say, movement of the pin 9 downwardly in the position of Fig. 3 will cause the dog 15 to travel up upon the head 12 and obtain a fresh bite upon the same, and the same movement will cause the dog 16 to press against the head 12 and tend to rotate it in the direction of the hands of a clock. Reverse movement would call the dog 15 into play and cause the dog 16 to travel up upon the head and obtain a fresh hold. In this manner the worm 4 is rotated, and with it the entire body of the hammer is rotated, provided the gear 6 and its connecting parts are rigidly held.

I will now describe the modified form of construction shown in Figs. 4 to 7, inclusive. I employ a similar lever 8^a , which is pivoted at 7^a and which has a pin 9^a engaging in a slot 10^a . I employ a similar reciprocating driving-plate 1^a , actuated in the same manner as above described. The part 17 is integral with the body of the hammer, and in this part the lever 8^a is pivoted. Upon the non-rotating part 3^a are mounted two ratchet or serrated surfaces 18 and 19, and mounted over the non-rotating parts and within these ratchets are two collars 20 and 21, which are secured to the non-rotating portion 17 by screws taking through slotted openings, so that said parts 20 and 21 have a limited movement in rotation. The lever 8^a has an extension 22, which is seated loosely in a slot 23 of the plate 20, and the body of the lever 8^a is in like manner seated loosely in a slot 24 of the plate 21. If now the lever 8^a is moved upon its axis, it will cause a slight movement in rotation of the plates 20 and 21 in opposite directions from each other. Mounted upon said plate 20 is a dog 25, which en-

gages the ratchet 18, and mounted upon the plate 21 is a dog 26, which engages the ratchet 19. These dogs are held up to work by springs. It will now be evident that if the plate 1^a is given reciprocatory movement the pin 9^a will be moved back and forth in the slot 10^a, and through such reciprocatory movement of the lever 8^a the plates 20 and 21 will be given reciprocatory movement in opposite directions from each other. This will cause the dogs 25 and 26 to engage the ratchets 18 and 19 alternately and alternately to gain fresh hold upon said ratchets upon the reverse movement.

15 It will be seen that the general principles of constructions are the same in Figs. 4, 5, 6, and 7 as they are in Figs. 1, 2, and 3, and I do not wish to limit myself absolutely to the constructions shown and described.

20 Having thus described my invention and its method of operation, what I claim is—

25 1. In a flue-cleaner the combination with a non-rotary part and a rotary part provided with a hammer, of means for causing rotation of the part carrying the hammer, comprising a reciprocable plate actuated by the engine, an engine in said rotary part, a lever pivoted to said rotary part and reciprocated by said driving-plate, a worm, a ratchet mechanism 30 for rotating said worm and actuated by said lever, a gear mounted upon said non-rotary part and engaging said worm, whereby said hammer is caused to rotate.

35 2. A flue-cleaner comprising the combination of a rotary part and a non-rotary part of an engine carried by said rotary part, a driving-plate actuated by said engine, a reciprocable lever actuated by said driving-plate, said lever being pivoted to said rotary part, a 40 worm mounted upon said rotary part, a ratchet upon said worm, dogs pivoted to said reciprocable lever, and engaging said ratchet, said dogs being pivoted oppositely upon the head of said lever in such manner that when 45 said lever is reciprocated in one direction, one dog will engage said ratchet and move it, and the other will engage it to take a fresh bite, and upon the opposite movement of said lever the dog having obtained a fresh

50 bite moves said ratchet while the opposite dog obtains a fresh bite, a gear engaging said worm and mounted upon said non-rotary part, whereby movement in the same direction is given to the said ratchet and said worm by both movements of said lever. 55

3. A flue-cleaner comprising the combination with a rotary part and a non-rotary part of an engine carried by said rotary part, a reciprocable plate provided with a slot inclined to the axis of the machine, said plate 60 being actuated by said engine and reciprocating in a plane parallel with the axis of the machine, a reciprocable lever, a roller on said lever engaging in said inclined slot upon said reciprocable plate, said reciprocating lever 65 being pivoted to said rotary part, a worm pivoted in said rotary part, a ratchet on the head of said worm, dogs pivoted to said reciprocable lever and engaging said ratchet, said dogs being pivoted to said lever diametrically opposite the pivot of said lever, and both dogs engaging upon the same side of 70 said ratchet, a gear rigidly mounted upon said non-rotary part and engaging said worm, whereby the reciprocatory movement of said engine, through said reciprocable plate and said reciprocable lever causes alternate movement of said dogs, thus imparting movement in one direction of said rotary part. 75

4. In a flue-cleaner the combination with 80 a non-rotary part, a rotary part provided with a hammer, and an engine for actuating said hammer, of means for causing the movement of said rotary part comprising a reciprocable plate provided with an inclined 85 slot, a reciprocable lever pivoted to said rotary part, a roller on said lever engaging in said slot, dogs pivoted to said reciprocable lever, a worm on said rotary part, a gear mounted upon said non-rotary part engaging 90 said worm, and a serrated or toothed head on said worm engaging said dogs.

In witness whereof I have hereunto set my hand in the presence of two witnesses.

CYRUS S. DEAN.
